UNITED STATES PATENT OFFICE.

NATHANIEL CRANK, OF HILL CITY, KANSAS.

VAPOR-CABINET.

1,010,595.

Specification of Letters Patent.

Patented Dec. 5, 1911.

Application filed April 17, 1911. Serial No. 621,718.

To all whom it may concern:

Be it known that I, NATHANIEL CRANK, a citizen of the United States, residing at Hill City, in the county of Graham and State of Kansas, have invented new and useful Improvements in Vapor-Cabinets, of which the following is a specification.

This invention relates to certain new and useful improvements in vapor cabinets and 10 the object of the invention is to generally improve and simplify devices of this character.

The invention consists in certain devices and combination of devices to be now described and claimed.

In the drawings: Figure 1 is a perspective view of the invention, Fig. 2 is a longitudinal vertical sectional view of Fig. 1, Fig. 3 is a section on the line 3—3 of Fig. 2, and 20 Fig. 4 is a section on the line 4—4 of Fig. 2.

1 designates the base of the cabinet which is of pan-like character, legs 2 depending from the same. The top is composed of two sections 3 and 4 hingedly connected to opposite ends of the base 1.

5 and 6 designate closures which are hingedly connected to the sections 3 and 4 respectively and which are formed to provide an opening 7, in which latter the neck of the 30 user is received.

8 designates a hinged leg which is adapted to support the section 4 when the latter is in lowermost open position.

The base 1 is provided with a top 9 which 35 is formed with a series of openings 10 and is provided with an upwardly extending box-like part 11, the latter being formed on each side at each of the ends of the latter with vertical openings 12, adapted to receive 40 pins 13 which latter are passed through openings 14 of a seat 15, the openings 14 registering with the openings 12 of the box-like part 11, whereby it will be obvious that the seat 15 may be raised or lowered to provide 45 a seat of desired height. The seat 15 is formed with openings 16.

By reference to Fig. 3, it will be seen that the box 11 communicates with the pan-like base 1, whereby the vapor from the pan base 50 enters the box 11 and egresses through the openings 12 and 16 as well as through the openings 10 of the top plate 9 of the base. The base 1 is formed with a compartment 17 which communicates by means of a pipe 18

with the boiler 19 in which latter the water 55 is confined.

20 designates the burner for supplying heat to the boiler 19.

In the compartment or chamber 17 there is a medicine container or can 21 which is 60 spaced from the side walls and the bottom of the chamber 17 and has a tube 22 connected thereto which latter extends through the top of the section 4 and has a mouth piece 23 whereby the occupant of the cabinet 65 may inhale the fumes from the medicinal receptacle 21. It will be noted that the steam or vapor enters receptacle 17 from the pipe 18 and egresses from the receptacle through the opening 24 to escape into the 70 base 1. Thus the steam or vapor is introduced into the cabinet in contact with the medicinal receptacle 21, tending to vaporize the medicine in the latter, after which it escapes from the openings 24 to enter the 75 interior of the cabinet.

25 designates sockets carried by the opposite side walls of section 3 in which are removably fitted the depending ends of a U-shaped supporting rod 26. 80

27 designates a water tank having hooks 28 secured thereto the hooks engaging over the supporting bar 26 and thereby supporting the water tank 27 and permitting the latter to be slid from one side to the other 85 of the cabinet. Depending from the tank 27 is a rubber tube 29 having a spray nozzle 30 secured thereto, by means of which the occupant may obviously spray himself with cold water whenever desired. 90

31 designates a thermometer by means of which the temperature of the cabinet can be ascertained. The neck of the medicinal container projects through the cover plate 9, from which it may be supported in any convenient manner. 95

What I claim is:

1. In a vapor cabinet, a base of pan-like character, a compartment in said base, said compartment having communication with the base interior, a cover plate for the base, a pipe extending into said compartment, and a medicinal container having its body arranged in said compartment and having its neck projecting through the cover plate, 100 said pipe having its discharge end arranged adjacent to but spaced from said medicinal container, said neck of the medicinal con-

tainer having a rubber tube connected thereto.

2. In a vapor cabinet, a base of pan-like character, a compartment in the base, 5 one wall of said compartment being formed with an opening adjacent the bottom of the base to communicate with the compartment, a medicinal container in the compartment having its bottom located above the bottom 10 of the base, a pipe extending into the compartment adjacent the top thereof and ar-

ranged to have its free open end spaced from the container, and means to supply steam or vapor to said pipe.

In testimony whereof I have hereunto set 15 my hand in presence of two subscribing witnesses.

NATHANIEL CRANK.
